UNITED STATES PATENT OFFICE.

CHARLES P. BEISEL, OF WILKESBARRE, PENNSYLVANIA.

DESIGN FOR A BADGE.

SPECIFICATION forming part of Design No. 34,433, dated April 30, 1901.

Application filed March 30, 1901. Serial No. 53,737. Term of patent 3½ years.

● *To all whom it may concern:*

Be it known that I, CHARLES P. BEISEL, a citizen of the United States, residing at Wilkesbarre, in the county of Luzerne and 5 State of Pennsylvania, have invented and produced a new and original Design for a Badge, of which the following is a specification.

This invention relates to a new and original 10 design for a badge, and the essential features reside in the design as illustrated in the accompanying facsimile drawings, wherein—

Figure 1 is an elevation of a badge embodying the features of the design. Fig. 2 is a 15 transverse vertical section of the same.

The design is characterized by a body 1, having the shape of a frying-pan and provided with a handle 2, the latter being formed with an elongated projection 3. Within the 20 body 1 is the representation 4 of "Uncle Sam" in the foreground, shown supported on

an elevated object 5. A buffalo 6 is also shown in the act of running from Uncle Sam, and on the stretched tail 7 thereof is shown attached a frying-pan 8. Uncle Sam is also shown in the act of kicking a pan 9, several of the latter appearing between the buffalo and Uncle Sam as flying through the air or space between said representations. The complete illustration alludes to the Pan-American Ex- 30 position.

Having thus described the invention, what is claimed as new is—

The design for a badge, as herein shown and described.

In testimony that I claim the foregoing as my own I have hereto affixed my signature in the presence of two witnesses.

CHAS. P. BEISEL.
